[57] CLAIM

The ornamental design for a combined book end bracket and shelf assembly, as shown and described.

DESCRIPTION

FIG. 1 is a left side elevational view of a combined book end bracket and shelf assembly showing our new design, the right side being a mirror image of that shown; FIG. 2 is a front elevational view thereof;

FIG. 3 is a rear elevational view thereof;

FIG. 4 is a bottom plan view thereof;

FIG. 5 is a top plan view thereof; and

FIG. 6 is a fragmentary top, front, and left side perspective view thereof.

The broken-line depiction of shelf standards in the views is for illustrative purposes only and forms no part of the claimed design.
